Int. Cl. D24—02

U.S. Cl. D24—1

FIG. 1

FIG. 2

FIG. 1 is a perspective view of a dentist's lighting instrument showing our new design;

FIG. 2 is an end elevational view;

FIG. 3 is an elevational view looking toward the end of the dentist's lighting instrument opposite that shown in FIG. 2;

FIG. 4 is a side elevational view looking toward the side of the dentist's lighting instrument opposite that shown in FIG. 1; and

FIG. 5 is a bottom plan view thereof.

The light-transmitting conduit and the electrical power supply line of the dentist's lighting instrument are shown broken away in the several figures of the drawings to indicate indeterminate lengths.

We claim:

The ornamental design for a dentist's lighting instrument, substantially as shown and described.
